UNITED STATES PATENT OFFICE.

ALFRED T. KRUSE, OF DEFIANCE, OHIO, ASSIGNOR TO THE AMERICAN STEEL PACKAGE COMPANY, OF DEFIANCE, OHIO, A CORPORATION OF OHIO.

SHEET-METAL PACKING-CASE.

No. 884,669.

Specification of Letters Patent. Patented April 14, 1908.

Application filed September 20, 1905. Serial No. 279,263.

To all whom it may concern:

Be it known that I, ALFRED T. KRUSE, a citizen of the United States, residing at Defiance, in the county of Defiance and State of Ohio, have invented new and useful Improvements in Sheet-Metal Packing-Cases, of which the following is a specification.

The invention relates particularly to improvements in bottoms for sheet-metal packing-cases of rectangular shape and of the general form and construction disclosed in my co-pending applications for Letters Patent, filed February 4, 1904; Serial Numbers 192,057 and 192,058.

15. The paramount object of the present invention is to provide a generally improved bottom for packing-cases of this class which will be of great strength and durability and which will, at the same time, not only tend 20 to strengthen and support the lower edges of the sides and ends to which it is attached, but, by reason of the particular construction, hereinafter shown and described, be better adapted to support the case with its contents upon the ordinary conveyer now in 25 common use by brewers and form a convenient friction-bearing surface for the same.

With these ends in view, the invention consists in the novel construction, herein- 30 after described illustrated in the accompanying drawings, and particularly pointed out in the appended claims.

Referring now to the accompanying drawings, forming a part of this specification, 35 Figure 1, is a longitudinal sectional view of the lower portion of a rectangular packing-case provided with the improved bottom. Fig. 2, is a detached detailed view of the same. Fig. 3, is a perspective view of the 40 improved bottom. Fig. 4, is a detached detailed view of the same showing the marginal side and end turned up preparatory to attachment to the side and end of the case. Fig. 5, is a cross sectional view of the lower 45 portion of a case provided with the improved bottom. Fig. 6, is a plan view of a single blank of sheet-metal showing notched formation of the improved bottom.

Similar numerals of reference designate 50 like parts throughout all the figures of the drawings.

The improved bottom is preferably con-

structed of a single blank of sheet metal 1, having its corners notched, as at "a" and of a depth corresponding to the width of the marginal sides and ends "b" which are first bent over and about to form the marginal channel grooves "c," as shown in Figs. 3 and 4, adapted to take over the beading 2, inclosing a wire 3, formed about the lower edges of the sides and ends 4, of the case to form a double beading, 4^a, as shown most clearly in Figs. 1, 2, and 5, of the drawings.

In order to further strengthen and support the bottom and provide a friction-bearing surface for the same upon the conveyer, frequently employed in transporting cases of this kind, a downwardly-extending supporting-rib or panel 6, is formed with the bottom, extending lengthwise thereof, and, in the present instance, at the center of the bottom. It will be understood, however, that a number or series of supporting-ribs or panels may be formed in the bottom, if found necessary or desirable.

It will be observed that the bottom or friction-bearing surface of the supporting-rib or panel is formed in alinement with the lower edge of the double beading 4^a, hereinbefore referred to. The sides 7, formed with the supporting-rib or panel are of a depth corresponding to the thickness of the double beading 4^a and in order that the ends of said sides 7, may abut up against the double beading 4^a, formed at the lower edges of the ends 80 of the case, notches "d," (see Figs. 3 and 6) are formed in the ends of the bottom opposite where the sides 7, of the supporting-rib or panel 6, are to be formed and of a width substantially corresponding with the depth 85 of the sides. There is thus formed between the notches "d," a short tongue "e" (see Fig. 6) or extension of the friction-bearing surface of the supporting-rib or panel, adapted to be bent over and about the beading 2, 90 formed at the lower edges of the ends of the case. As this tongue does not have so far to extend about the beading 2, as the marginal ends "b," forming the channel grooves "c," it is formed shorter, as shown most clearly in Fig. 6, of the drawings.

A horizontally-arranged rectangular supporting-plate 8, is mounted and interposed between the sides and ends of the case and is

- provided about its edges with a strengthening-flange 9, abutting against said sides and ends and may be secured thereto by means of rivets, or in some other suitable manner. The 5 plate 8, is provided with a series of openings and annular inwardly-inclined downwardly-extending flanges 10, formed about said openings and adapted to support the bodies of the bottles.
- 10 Having thus described my invention, without having attempted to set forth all the forms in which it may be made, or all the modes of its use, I declare that what I claim and desire to secure by Letters Patent, is—
- 15 1. In a sheet-metal packing-case, the combination with sides and ends secured at the corners of the case and provided with a beading inclosing a wire around the lower edges thereof; of a bottom secured thereto and provided with a downwardly-extending supporting-panel extending lengthwise thereof, and sides formed with said panel and having the ends thereof abutting against said beading.
- 20 2. In a sheet-metal packing-case, a case 25 consisting of side and end walls provided with a beading at their lower edges, a bottom secured thereto by having its marginal sides and ends bent over and about said beading to form a second beading, and a supporting-panel formed therein and having its sides abutting against said first mentioned beading.
- 30 3. In a sheet-metal packing case provided with a beading about the lower edges thereof, a bottom secured thereto, a supporting-panel formed in said bottom, and sides formed with said panel and having the ends thereof abutting against said beading.
- 35 4. A sheet-metal packing-case, consisting of side and end walls having a beading about 40 the bottom edges, a bottom secured thereto by having its edges bent about said beading on the side and end walls so as to form a double beading, a supporting-panel formed therein and having its bottom or friction-bearing surface in alinement with said double beading, and sides formed with said supporting-panel and having the ends thereof abutting against said first mentioned beading.
- 45 5. A bottom for sheet-metal packing-cases, consisting of a single blank of sheet metal having notched corners, a pair of notches formed therein in alinement with said notched corners, and a tongue intermediate said pair of notches and of less length 50 than said notches.
- 55 6. A bottom for sheet-metal packing-cases, consisting of a single blank of sheet metal having its edges bent over and about forming marginal channel grooves, a pair of notches formed therein, and a supporting-panel having its sides in alinement with said notches and abutting against said marginal channel grooves.
7. A bottom for sheet-metal packing-cases, consisting of a single blank of sheet metal having notched corners, a pair of notches formed therein in alinement with said notched corners marginal beadings in alinement with said notched corners and a downwardly-extending supporting-panel having its sides in alinement with said pair of notches. 65
8. A bottom for sheet-metal packing-cases, consisting of a single blank of sheet metal having notched corners, and a pair of notches formed therein in alinement with said notched corners. 70
9. A bottom for sheet-metal packing-cases, consisting of a single blank of sheet metal having a pair of notches formed therein, marginal channel grooves in lateral alinement with said notches and a downwardly-extending supporting-panel having its sides in alinement with said pair of notches. 80
10. A bottom for sheet-metal packing-cases, consisting of a sheet of metal having its corners cut away and its marginal edges bent over and about to form a beading, and a supporting-panel formed therein and having its sides adapted to abut against said beading. 85
11. A bottom for sheet-metal packing-cases, consisting of a sheet of metal having a supporting-panel formed therein and adapted to abut against the lower edges of the case, and a tongue formed at the ends of said supporting-panel and adapted to be secured to the lower edges of the case. 90
12. In a sheet-metal packing-case, the combination with a beading formed about the lower edges of the case; of a bottom provided with a downwardly-extending supporting-panel having a friction-bearing surface flush with said beading, and vertical sides formed with said panel and having the ends thereof abutting against said beading. 100
13. A bottom for sheet-metal packing-cases, consisting of a single blank of sheet metal provided with a channel groove about its marginal edges, notches formed therein opposite where the sides of a supporting-panel are to be formed, a supporting-panel crimped in said blank of sheet metal and provided with vertical sides abutting against said channel groove, and carrying a friction-bearing surface flush with said channel groove. 110
14. In a sheet-metal packing-case, the combination with side and end walls provided with a beading at the lower edges thereof; of a bottom having its corners cut away and its marginal edges bent over and about said beading to form a second beading, and a panel formed in said bottom and provided with sides having the ends thereof abutting against said beading. 115
15. A bottom for sheet-metal packing-cases, consisting of a single blank of sheet metal having notched corners, a pair of notches formed therein in alinement with said notched corners marginal beadings in alinement with said notched corners and a downwardly-extending supporting-panel having its sides in alinement with said pair of notches. 120
16. A bottom for sheet-metal packing-cases, consisting of a single blank of sheet metal having notched corners, and a pair of notches formed therein in alinement with said notched corners. 125

15. In a sheet-metal packing-case, the combination with suitable walls, and a beading secured thereto; of a bottom secured to said beading and provided with a supporting-panel having the ends of its sides abutting against said beading and carrying a friction-bearing surface flush with said beading.

In testimony whereof I affix my signature, in presence of two subscribing witnesses.

ALFRED T. KRUSE.
